Des. 212,981
Patented Dec. 17, 1968

212,981

WRITING INSTRUMENT

Sidney Laybourne, 2642 64th Ave.,
Oakland, Calif. 94605

Filed Nov. 25, 1966, Ser. No. 4,805

Term of patent 14 years

(Cl. D74—17)

FIGURE 1 is a side elevational view of a writing instrument showing my new design;

FIGURE 2 is a top plan view thereof;

FIGURE 3 is a bottom plan view thereof;

FIGURE 4 is an end elevational view from the back end thereof;

FIGURE 5 is an end elevational view from the front end thereof; and

FIGURE 6 is a top perspective view thereof on an enlarged scale.

I claim:

The ornamental design for a writing instrument, substantially as shown.
